PIPE RAILING ATTACHING FITTINGS

Adolph A. Wagner, Milwaukee, Wis., assignor to R & B Wagner Inc., Milwaukee, Wis., a corporation of Wisconsin

Application April 5, 1956, Serial No. 576,399

9 Claims. (Cl. 287—23)

This invention relates to improvements in pipe-railing- 15 attaching fittings.

It is the object of the present invention to provide a fitting between a pipe-railing post and a stringer flange which improves the mechanical interconnection of the post to the stringer and improves the appearance of 20 the connection. The fittings of the present invention may be prefabricated by mass production techniques and hence supplied at relatively low cost. The structure of the fitting is desirably such that it is universally applicable to connect pipe-railing posts either at a right angle to the stringer flange or at an inclined angle to the stringer flange.

A desirable feature of certain fitting embodiments of my invention resides in the substantial alignment of the skirt portion of the fitting with the web of the stringer. The visual effect is unitary and the appearance of the connection enhanced. The width of the fitting over a substantial portion of its length is desirably substantially equal to the width of the stringer flange, thus further enhancing the unitary appearance of the connection.

In the fitting of my invention a superior mechanical union between the post and stringer is achieved. This is at least partly attributed to my structure in which the plate portion of the fitting is spaced by its skirt from the flange of the stringer. Accordingly, the post is welded to the plate at a point spaced from the end of the post which abuts the flange.

Other objects and advantages of the invention will be more apparent from an examination of the following disclosure in which:

Fig. 1 is a fragmentary elevation of a pipe railing and channeled stringers to which the pipe-railing posts are connected by fittings according to my invention.

Fig. 2 is a fragmentary cross sectional view taken along the line 2—2 of Fig. 1.

Fig. 3 is a cross section taken along the line 3—3 of Fig. 2.

Fig. 4 is a cross section taken along the line 4—4 of Fig. 2.

Fig. 5 is a fragmentary perspective view of the connection shown in Figs. 2, 3 and 4.

Fig. 6 is a cross section similar to Fig. 3 but showing a modified embodiment of the invention in which the pipe post is connected at an inclined angle to the stringer.

Fig. 7 is a perspective view of the fitting used in Fig. 6.

Fig. 8 is a view similar to Fig. 4 and showing my fitting applied to a plate stringer having a bolted flange.

Fig. 9 is a fragmentary side elevation of the device of Fig. 8.

In Fig. 1 generally conventional pipe-railing construction is illustrated, including a hand rail 10, a guard rail 11, posts 12 and 13, a platform channeled stringer 14 and a stairway channeled stringer 15. The platform floor is indicated at 8 and the stairway steps at 9. The post 12 is at a right angle to the upper flange 16 of channeled stringer 14 and the post 13 is at an inclined angle

2

to the upper flange 17 of channeled stringer 15. As best shown in Fig. 4 the stringer 14 further comprises a web 18 and the stringer 15 further comprises a web 19.

To connect the post 12 with the flange 16 of stringer 5 14, I provide a fitting or flange comprising a deck plate 21 having a laterally enlarged central portion 22 provided with a circular opening 26. The margins of central portion 22 are desirably oblong and preferably elliptical in outline.

10 At opposite sides of the central portion 22 the deck plate has end portions 23 with rectilinear, parallel side margins spaced a distance substantially equal to the width of the stringer flange 16. The ends 20 of the plate 21 are desirably semicircular as illustrated.

The margins of the plate are provided with a depending skirt 32 conforming to the contour of the plate margins. Accordingly the skirt has rectilinear portions 24, curved side portions 25 and semicircular end portions as best shown in Fig. 5. The skirt is desirably fabricated in a stamping operation, the deck plate and skirt being integral and of substantially the same thickness.

The post 12 extends through the opening 26 and its end abuts the stringer flange 16, as shown in Fig. 3. The post 12 is welded to the margins of the opening 26 as 25 indicated at 29.

The deck plate is further provided with apertures 27 near its ends to receive bolts 28 which removably connect the fitting to the stringer flange 16. The bolt holes 27 are desirably positioned so that peripheral portions of the bolt heads 31 will align with portions of the skirt 32, thereby to transmit pressure of the bolt directly to the skirt and against the flange 16. Other peripheral portions of the bolt heads 31 bear on portions of the plate 21 extending from the inner surface of the skirt and portions 35 24 toward the opening 26 for the post 12 so that the bolt heads also seat on plate portions spaced from the skirt.

As best shown in Fig. 5 the attached fitting blends smoothly with the stringer to give the connection a unitary appearance. The rectilinear portions 24 of the skirt side wall 32 parallel the exposed face of web 18 and desirably align therewith. From Fig. 4 it will be noted that the opposite rectilinear side wall 33 of the skirt also is parallel to the edge of the flange 16 and desirably aligns therewith. The curved portions 25 of the skirt may overhang the edges of flange 16, as shown in Fig. 4.

In Figs. 6 and 7 I disclose the interconnection of pipe post 13 with the flange 17 of inclined stair stringer 15. The parts of the fitting are substantially identical with 50 those of the fitting previously described and have been given the same reference characters. The only difference between the fitting shown in Figs. 6 and 7 and the fitting shown in Figs. 2—5 is the provision for a post-receiving aperture 35 which is elliptical in outline, instead of being 55 circular in outline. Accordingly, the post 13 may be received through the opening 35 at an inclined angle to the flange 17 of the stringer 15.

Note that in the fitting of Figs. 6 and 7 the elliptical opening 35 is complementary to the elliptical side walls 60 25 of skirt 32 and complementary to the elliptical side margins 22 of the plate. For convenience in fabrication the fitting may be standardized for fabrication of the plate margin 22 and skirt portion 25 in oblong or elliptical outline. Either a circular opening 26 or an elliptical opening 35 may then be punched in the deck plate depending on the ultimate use of the fitting.

In Fig. 8 application of my fitting to a platform or 65 stairway plate stringer 36 is illustrated. To the side of plate stringer 36 I fasten an angle bracket 37 comprising flanges 38, 39 connected at a right angle. In this embodiment of the invention the flange 38 is fastened to the plate stringer 36 by bolts 42 having square nuts 43.

The centerline of the holes for bolts 42 is spaced laterally from flange 39 a distance substantially equal to the spacing from the centerline of nut 43 to one of its flat sides. Accordingly, flat sides of the respective nuts 43 will lock against the flange 39 and the nuts need not be held while tightening the bolts 42.

The same relation is true of nuts 44 for bolts 45 which fasten the fitting 21 to the flange 39. Respective flat sides of the nuts 44 lock against the flange 38.

The respective nuts 43, 44 function as gussets or braces between the flanges 38, 39 of bracket 37, thus eliminating need for any other bracing means therebetween. For this purpose the respective bolt and nut sets 42, 43 and 45, 44 are staggered longitudinally of the bracket 37 so that each nut 43, 44 seats snugly in the corner between flanges 38, 39. The flanges 38, 39 are desirably at exactly 90° and there is no fillet therebetween. Accordingly, the respective nuts 43, 44 have surfaces which seat intimately against both flanges to serve as bracing therebetween.

The fitting 21 is positioned on the flange 38 in substantially the same manner as on flange 16 shown in Fig. 4.

I claim:

1. A fitting for connecting a pipe-railing post to a stringer flange, said fitting comprising an elongated plate having end portions with parallel sides spaced a distance approximately equal to the width of said flange and a laterally enlarged center portion wider than said flange and having curved side portions which merge with said parallel sides, and a depending marginal skirt integral with said plate and extending at a right angle thereto for engagement with said stringer flange, and an aperture formed in the enlarged portion of said plate and adapted to receive said post.

2. The device of claim 1 in which said plate is provided with bolt holes near its ends, and bolts therethrough having heads extending laterally from said holes, portions of said bolt heads bearing on the skirt and portions of said bolt heads bearing on plate portions spaced from the skirt.

3. In a device of the character described, the combination with a pipe post and a stringer having a side wall and a flange, of a fitting for connecting the post to the flange and comprising an elongated plate having end portions with parallel, rectilinear side portions spaced a distance approximately equal to the width of said flange and a laterally enlarged center portion wider than said flange and having curved side portions which merge with said rectilinear side portions, a depending marginal skirt integral with said plate and extending at a right angle thereto for engagement with said stringer flange, said skirt having parallel rectilinear and curved portions corresponding to the side portions of the plate, said plate being provided with bolt holes near its ends and bolts through said holes and connecting said fitting to said flange with the rectilinear side portions at one side of said plate and skirt substantially aligned with the stringer side wall, said plate being provided with an opening in its said enlarged central portion, said post extending through said opening with its end abutting the stringer flange, the side wall of the post spaced from its end being connected to said plate about said opening.

4. The device of claim 3 in which the curved side portions of the plate and skirt are generally elliptical, said opening being elliptical in outline to receive the pipe post at an angle to said plate, portions of said bolt heads bearing on the skirt and portions of said bolt heads bearing on plate portions spaced from the skirt.

5. The device of claim 3 in which the curved side portions of the plate and skirt are generally elliptical, said opening being circular in outline to receive the pipe post at substantially a right angle to said plate, portions of said bolt heads bearing on the skirt and portions of said bolt heads bearing on plate portions spaced from the skirt.

6. A fitting for connecting a pipe-railing post to a stringer flange, said fitting comprising an elongated plate having end portions with parallel sides spaced a distance approximately equal to the width of said flange and a laterally enlarged center portion having curved side portions which merge with said parallel sides, and a depending marginal skirt integral with said plate and extending at a right angle thereto for engagement with said stringer flange, and an aperture formed in the enlarged portion of said plate and adapted to receive said post, said stringer comprising a plate and said flange being part of a bracket having another flange in face relation to the plate, said flanges being disposed at a 90° angle, means bolting the respective flanges to the plate and to the fitting, said means including a nut having one surface flat against one flange and another surface flat against the other flange to mutually brace said flanges in 90° relation.

7. The device of claim 6 in which said means further comprises one set of nuts and bolts for one flange and another set of nuts and bolts for the other flanges, said sets being staggered longitudinally of the bracket for noninterference of their respective nuts.

8. A fitting adapted to connect a pipe-railing post to a stringer flange, an elongated plate having a peripheral skirt adapted for abutment on the stringer flange adjacent the ends of the fitting and having an enlarged central portion extending beyond the edges of the flange, said plate having an opening to receive the post in close-fitting relation for welding of the post periphery to the plate and having bolt holes adapted to receive bolts for connecting the fitting to the stringer flange, the bolt holes being adjacent the ends of the fitting for overlying the skirt by the bolt heads for transmitting bolt pressure directly to the skirt.

9. A fitting adapted to connect a pipe-railing post to a stringer flange, an elongated plate having a peripheral skirt adapted for abutment at the end portions thereof only on the stringer flange, said plate having an opening to receive the post in close-fitting relation for welding of the post periphery to the plate and having a bolt hole adapted to receive a bolt for connecting the fitting to the stringer flange, the skirt comprising end portions and rectilinear side portions for bearing on the stringer and laterally enlarged central portions wider than the stringer flange whereby pressure of the bolt on the fitting acts through the end and side portions of the fitting skirt and the fitting-post weld is free from stresses due to bolt pressures.
